UNITED STATES PATENT OFFICE.

FRANK O. LUECK, OF TOMAH, WISCONSIN.

PRICE-TICKET AND SAMPLE HOLDER.

SPECIFICATION forming part of Letters Patent No. 673,716, dated May 7, 1901.

Application filed December 31, 1900. Serial No. 41,679. (No model.)

To all whom it may concern:

Be it known that I, FRANK O. LUECK, a citizen of the United States, residing at Tomah, in the county of Monroe and State of Wisconsin, have invented certain new and useful Improvements in Price-Ticket and Sample Holders, of which the following is a specification, reference being had therein to the accompanying drawings.

My invention relates to a device adapted to receive and be connected with not only the price-tag or reversible ticket usually attached to bolts of cloth or of other textile fabrics, but also samples of said cloth, which device and samples can be temporarily removed from the interior of the bolt of cloth and replaced therein. Dry-goods merchants are subjected to great loss of materials by the common request of customers for samples of perhaps three or four pieces of cloth to show to persons at home or to select from at a later date, a strip an inch or more wide and three to six inches long being cut from each bolt and no sale made. Later on another customer may come to buy one or more yards of the sampled cloth, but generally objects to have the sampled width included in the purchase, and therefore, to make a sale, an inch or more of the whole width of cloth is lost to the merchant, and this loss is important on expensive cloths and is constantly repeated for nearly every sale made from a bolt of cloth. The objects of my invention are to prevent these successive losses and to limit the loss to only one inch of cloth per bolt even if a series of samples had been given and a series of intervening sales had been made of portions of said bolt. I accomplish these objects by means of combined price-ticket holders and sample-holders shown in the accompanying drawings, in which—

Figure 1 is a perspective view of a bolt of cloth with a combined price-ticket holder and sample-holder constructed in accordance with my invention. Fig. 2 is a perspective view, on a larger scale, of the combined price-ticket holder and sample-holder constructed in accordance with my invention. Fig. 3 is a longitudinal vertical section of the front half of the same. Fig. 4 is a modification of the form shown in Fig. 1.

In said drawings, A represents a bolt of

cloth wound around a central block or board B, as usual. Projecting over one end of said block is the tag or ticket holder C, which consists of a strip of thin sheet metal, as tinned iron, folded upon itself, preferably about half-way of its length, to constitute two leaves c and d. About half an inch from their fold said leaves are bent together down at right angles to their horizontal top surfaces to constitute a support e for the back of the card, tag, or ticket E, upon which are generally written the cost of the cloth per yard, its selling price, the number of yards, &c. To support the bottom edge of the ticket E, the leaves cd are bent together horizontally within about a sixteenth of an inch of their fold to constitute a narrow shelf f as a support for the bottom edge of said ticket.

To retain the ticket E secured to its back support e, a narrow strip of thin sheet metal G, slightly longer than the width of the leaves cd, is placed against the back of the card-support e, and its ends g are folded forward over the ends of the price-card or in position to retain it. Said strip G is thus kept immovably secured to the leaves cd of the sample-holder, as it is prevented from moving up by abutting against the bottom of the leaf d and is prevented from moving down on account of its ends g abutting upon the narrow shelf f. The leaves cd constitute a portfolio, between which are placed samples of the cloth or the long strip from which samples are to be cut. Through the strip G one or two small nails or tacks h are made to pass, to be pushed into the end of the board B to lightly anchor the device to said board. When samples of the cloth are desired, the combined ticket-holder and sample-holder is pulled out from between the board B and the inner coil of the bolt of cloth, a sample removed, and the device containing the balance of samples replaced in the same location from which it had been withdrawn.

In the modification shown in Fig. 4 the leaves cd are united at their back ends k, or, in other words, the leaf c is bent upon itself at k and folded under, the bottom portion extending forwardly substantially up to the vertical front end of the device, thus providing a pocket having open sides for the reception of samples of cloth, the parts retaining

the card E being similar to those shown in the other figures.

Having now fully described my invention,
I claim—

- 5 1. A holder for a price-ticket and samples of cloth, consisting of leaves of thin sheet metal joined at one end, and having said joined end bent downwardly and then bent outwardly in combination with a narrow strip 10 of metal bearing transversely against the back of the downward portion and having its ends bent forwardly and toward each other substantially as described.
- 15 2. A holder for price-ticket and carrier for samples of cloth, consisting of a narrow and substantially horizontal sheet of metal having its outer portion bent downwardly and the edge of said outer portion bent outwardly, in combination with a narrow strip of metal bearing 20 transversely against the back of the down-

ward portion and having its ends bent forward and toward each other substantially as described.

3. A holder for a price-ticket and for samples of cloth consisting of a narrow sheet of 25 metal bent upon itself and having its front portion vertical, the lower edge of said front portion being bent forwardly and its upper edge bent rearwardly, in combination with a narrow strip of metal bearing transversely 30 against the back of the vertical portion and having its ends bent forwardly and toward each other substantially as described.

In testimony whereof I affix my signature in presence of two witnesses.

FRANK O. LUECK.
